UNITED STATES PATENT OFFICE.

MORTON E. CONVERSE, OF WINCHENDON, MASSACHUSETTS.

EMBOSSING-MACHINE.

SPECIFICATION forming part of Letters Patent No. 554,053, dated February 4, 1896.

Application filed March 28, 1895. Serial No. 543,449. (No model.)

To all whom it may concern:

Be it known that I, MORTON E. CONVERSE, a citizen of the United States, residing at the town of Winchendon, State of Massachusetts, 5 have invented a new and useful Improvement in Embossing-Machines, of which the following is a specification.

This invention relates to wood-embossing machines, and particularly to machines for 10 embossing endless bands or hoops for drums and like articles; and it consists in the construction and novel arrangement of parts, as hereinafter specified, and particularly pointed out in the appended claims.

15 The object of my invention is to provide a machine upon which a number of endless bands or hoops may be placed for embossing and easily removed after the work shall have been done.

20 In the accompanying drawings, Figure 1 is a side elevation of an embossing-machine embodying my invention. Fig. 2 is a front elevation thereof, and Fig. 3 is a section through the line 3 3 of Fig. 1.

25 Referring by letter to the drawings, A designates the side frames of the machine, secured together by means of tie-rods a , and A' is a forwardly-projecting or overhanging arm secured to the upper portion of the side frames.

30 A² is a die-supporting mandrel. This mandrel, at its inner end, has a loose bearing in a hanger a' , and it rotates against antifriction-rollers a^2 , pivoted in cagings secured to the arm A'. An arm a^3 depends from the arm 35 A', and has at its end a roller a^4 , which bears against the lower side of the mandrel A² and serves to support the same. The mandrel A² is preferably tubular, so that a torch may be inserted for heating the dies.

40 The embossing-dies B are annular and are removably yet tightly fitted on the mandrel. I have shown but two dies; but it is obvious that a greater number may be employed if desired.

45 B' is the feed-roller upon which the bands or hoops b are placed for embossing. The feed-roller extends forward of the machine beneath the mandrel and is mounted on a shaft B², which has bearings in travelers b',

adjustable vertically in guideways b² of the 50 end frames.

The travelers are connected together by a boxing B³, and they are adjusted vertically to suit the feed-roller to the thickness of the work in hand by means of screws C, which 55 at their lower ends engage in tapped blocks or nuts C'. Bevel-gears c are secured to the upper portion of the screws C and bevel-gears C' on transverse shafts C², which are rotated through the medium of a hand-wheel C³. 60 The blocks or nuts C' are vertically movable in the end frames, but are held from rotary motion by any suitable means.

D is a cam-shaft, having cams d at its ends, which engage against the lower ends of the 65 blocks C'. When the cam-shaft is rocked by means of a hand-lever d', the cams will operate to raise the feed-roller and the bands thereon against the dies or to lower the same.

D' designates guide-fingers for the bands 70 or hoops. These fingers conform substantially to the cylindric feed-roller and are adjustably mounted on a rod d², extended from a plate d³, which is adjustably secured to the front traveler b' by means of set-screws extended 75 through arc-shaped slots in the plate.

It will be seen that the fingers are adjustable longitudinally of the feed-roller and also circumferentially thereof, so that the ends 80 may be regulated with relation to the dies.

Rotary motion is imparted to the feed-roller through the medium of the band-wheel E, the power-shaft E', the worm-wheel e thereon, and the worm-wheel e' mounted on the lower end of a vertical shaft e². The shaft e² has a spline 85 connection with a bevel-gear e³, so that there may be a vertical movement of the shaft relatively to the gear e³, and this gear e³ meshes with a bevel-wheel e⁴, mounted on the feed-roller shaft B².

The band-wheel E is loosely connected to its shaft E', so that said wheel may be in constant rotation without imparting motion to the machine. The machine may be placed in operative connection with the band-wheel 95 by means of a clutch F, operated by a clutch-lever f.

F' is a screw extended through a tapped

opening in the arm A' for the purpose of limiting the upward movement of the feed-roller.

From the above description the operation of the machine is quite obvious and need not be further described.

Having described my invention, what I claim is—

1. In an embossing-machine, the combination with the frame, of the vertically-adjustable feed-roller having its outer end free, the guide-fingers adjustable longitudinally and circumferentially of said feed-roller, the overhanging arm, the tubular die-mandrel supported thereby and the rollers bearing against the upper side of said mandrel substantially as specified.

2. In a machine for embossing hoops or endless bands, the combination with a frame, of the overhanging arm, the rotary mandrel supported thereby, the supporting-roller engaging the under side of the outer end of said

mandrel, the rotary feed-roller, screw mechanism for vertically adjusting said roller, and cam mechanism for raising and lowering said roller substantially as specified.

25

3. A machine for embossing endless bands, comprising a frame, an arm extended therefrom, a die-supporting mandrel having a bearing in a hanger extended from the arm, anti-friction-rollers engaging the rear end of the mandrel, antifriction-rollers engaging with the outer end of said mandrel, embossing-dies removably secured on the mandrel, a feed-roller below the mandrel, the adjustable guide-fingers in connection with the feed-roller and mechanism for operating the feed-roller, substantially as specified.
